UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

EASY OPENING CONTAINER

Application filed June 28, 1930. Serial No. 464,656.

The invention relates to new and useful improvements in easy opening containers and more particularly to the means for securing an inserted reclosure collar to the body of the container.

An object of the invention is to provide a means whereby an inserted collar may be bonded to the metal wall of the container by solder which is applied so as to be covered and protected from contact with the food products in the container, and which is applied in such a way as not to injure the lithographing on the outer face of the container.

In the drawings which show by way of illustration one embodiment of the invention:

Figure 1 is a vertical sectional view through the upper portion of the container embodying the improvements.

Figure 2 is a view through a portion of the container showing the rip strip removed and the end lifted from the container.

Figure 3 is an outer face view of a portion of the reclosure ring.

The invention is used for securing an inserted reclosure collar to the body of the container. As shown in the drawings the container body is indicated at 1, and one of the ends is indicated at 2. This end is secured to the body of a double seam 3.

The body wall is provided with an inwardly projecting bead 4 and with score lines 5 and 6 which form a rip strip 7. Located within the body of the container is an inserted reclosure collar 8 which is attached to the body of the container. There is also an inserted reclosure collar 9 attached to the end so that when the rip strip is removed this collar 9 forms a depending flange which slips down

over the collar 8 for reclosing purposes. The upper portion of the collar 8 is inset from the wall of the body, the thickness of the upper collar 9 so that said collars may be assembled in the manufacture of the can, one collar telescoping in part with the other. These collars are preferably made from metal by rolling or drawing the metal so as to provide a smooth unbroken edge for the collar as distinguished from a cut or torn edge. The

collars formed in this way and arranged as

shown in the drawings form no part of the present invention, but are shown and described and claimed in my co-pending application 465,742 filed July 3, 1930. The present invention is directed particularly to means for securing this collar 8 to the body of the container. This collar when inserted in the body is directly above the bead 4, but is not in any way attached to the bead. The bead serves as a support for preventing the collar from being forced into the container by the pressure applied to the outer edge thereof. In the form of the invention shown in the drawings the collar is provided with an inwardly projecting bead 10 which forms a recess 11 in the outer face of the collar. This recess preferably extends all the way around the collar. Again as illustrated in the drawings the recess 11 is provided with a soft solder 12 which is located at spaced intervals. The entire bead may be filled with solder, and instead of using a bead for housing the solder the soft solder may be applied to the inner face of the collar. The solder is of such a character that after the collar is inserted in the can with the solder applied thereto the can may be passed through an oven raised to a temperature of about 250° F., and this will cause the solder to melt and adhere to the inner wall of the body of the can. This is a temperature below the temperature that will in any way affect the lithographing on the outer face of the can. The solder being placed between the outer face of the collar and the inner face of the container is covered by the collar so that food products within the container will not come in contact with the solder. As noted, the solder is applied to the collar, the collar is then inserted in the container and placed against the bead 4 in the body wall of the container. The container body is then passed through an oven heated as stated, and this causes a bond of solder to be formed between the collar and the inner metal wall of the container body. The ends of the collar are preferably abutted so that the collar is of uniform diameter, and also of uniform thickness throughout.

While I have described the collars as

- formed by a rolling or drawing of the metal, it will be understood that it may be formed in other ways without departing from the spirit of the invention as set forth in the appended claims. It will also be noted that the solder as shown is applied at spaced points in the recess. While this greatly saves in the amount of solder used, it will be understood that the solder may be applied in other ways,
- 10 the essential feature residing in the placing of the solder between the collar and the wall of the container and the use of a solder which can be melted to form the bond joining the collar to the body without injuring the lithographing on the outer face of the container.
- 15

Having thus described the invention, what is claimed as new and desired to be secured by Letters Patent, is:—

1. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein, whereby when the collar is inserted in the container body and heat applied thereto said solder will form a bond between the collar and the container for securing the collar therein.
- 20
2. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein at spaced points, whereby when the collar is inserted in the container body and heat applied thereto said solder will form a bond between the collar and the container for securing the collar therein.
- 25
3. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein, whereby when the collar is inserted in the container body and heat applied thereto said solder will form a bond between the collar and the container for securing the collar therein.
- 30
4. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein at spaced points, whereby when the collar is inserted in the container body and heat applied thereto said solder will form a bond between the collar and the container for securing the collar therein.
- 35
5. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein, whereby when the collar is inserted in the container body and heat applied thereto said solder will form a bond between the collar and the container for securing the collar therein.
- 40
6. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein at spaced points, whereby when the collar is inserted in the container body and heat applied thereto said solder will form a bond between the collar and the container for securing the collar therein.
- 45
7. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein, whereby when the collar is inserted in the container body and heat applied thereto said solder will form a bond between the collar and the container for securing the collar therein.
- 50
8. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein at spaced points, whereby when the collar is inserted in the container body and heat applied thereto said solder will form a bond between the collar and the container for securing the collar therein.
- 55
9. An easy opening container having score lines in the body adjacent one end thereof forming a rip strip, a reclosure collar disposed within said container body, said collar having an inwardly projecting bead formed therein adjacent its lower edge and providing a recess on its outer face, said recess having soft solder applied therein, whereby when the collar is inserted in the container body and heat applied thereto said solder will form a bond between the collar and the container for securing the collar therein.
